ANIMAL REPELLENT

Robert T. Johnson, R.R. 3, Kingston,
Ontario, Canada

Filed Jan. 17, 1966, Ser. No. 669

Claims priority, application Canada Oct. 21, 1965

Term of patent 14 years

(Cl. D16—1)

FIGURE 1 is a top plan view of an animal repellent showing my new design, the opposite side of my repellent having substantially the same appearance;

FIG. 2 is a side view of the repellent illustrated in FIG. 1 when applied in an alternate position for display;

FIG. 3 is a cross-sectional view taken on line 3—3 of FIG. 1.

The broken line illustration of the evergreen foliage in FIG. 2 is shown for purposes of illustration.

I claim:

The ornamental design for an animal repellent, as shown and described.
